UNITED STATES PATENT OFFICE

113,999

DESIGN FOR A VENDING MACHINE CASING OR THE LIKE

Louis Steiner, New York, N. Y.

Application December 27, 1938, Serial No. 82,004

Term of patent 3½ years

To all whom it may concern:

Be it known that I, Louis Steiner, a citizen of the United States and a resident of the city, county, and State of New York, have invented a new, original, and ornamental design for a Vending Machine Casing or the Like, of which the following is a specification, reference being made to the accompanying drawing, forming a part thereof.

The drawing is a perspective view of the vending machine casing showing my new design.

I claim:

The ornamental design for a vending machine casing or the like, as shown.

LOUIS STEINER.
